CLAIM

The ornamental design on an ovalesque sling bag with folds, as shown and described.

DESCRIPTION

FIG. 1 is a front plan view of an ovalesque sling bag with folds showing folds at the neck of the bag, the bag has shading indicating a first preselected fabric;

FIG. 2 is a right perspective view of FIG. 1, the left perspective view is a mirror image thereof;

FIG. 3 is a top perspective view of FIG. 1,

FIG. 4 is a bottom perspective view of FIG. 1;

FIG. 5 is a right side perspective view of FIG. 1 of an ovalesque sling bag with folds, now showing optional closure devices on the front and side of the bag; the left side perspective view being a mirror image thereof;

FIG. 6 is a right side perspective view of FIG. 1 of an ovalesque sling bag with folds, now showing a fold over the bottom edge; the left side perspective view being a mirror image thereof;

FIG. 7 is a bottom perspective view of FIG. 6;

FIG. 8 is a right side perspective view of FIG. 1 of an ovalesque sling bag with folds, now showing an inverted folded gusset with an optional zipper; the left side perspective being a mirror image thereof; and,

FIG. 9 is a bottom perspective view of FIG. 8.

The broken lines showing of hardware (e.g. zipper, d-rings, hooks) as well as the position of the hardware relative to the claimed design and any other broken lines including the carry strap and stitching are to show environment only and are not part of the claimed design.
